UNITED STATES PATENT OFFICE.

MARIUS LATOUR, OF PARIS, FRANCE, ASSIGNOR TO LATOUR CORPORATION, OF JERSEY CITY, NEW JERSEY, A CORPORATION OF DELAWARE.

ELECTROMAGNETIC-WAVE-GENERATING SYSTEM.

Original application filed July 15, 1920, Serial No. 396,499, and in France February 15, 1916. Divided and this application filed October 30, 1923. Serial No. 671,640.

(GRANTED UNDER THE PROVISIONS OF THE ACT OF MARCH 3, 1921, 41 STAT. L., 1313.)

The present invention relates to an improved generating system for the electromagnetic wave transmission of speech using thermionic valves or elements, and relates 5 more particularly to dispositions of microphone attachments in wireless telephone stations.

The invention will be more particularly described with reference to the accompanying drawings in which:

Figure 1 shows diagrammatically one form of arrangement for feeding an antenna.

Figure 2 is a diagram showing a modified 15 form of construction.

The thermionic valve generator or element 1 contains as is usual an anode 2, a grid 3, and a filament 4 heated from a battery 5. The aerial 6 is connected to the 20 ground 7 through a self-inductance coil 8. A second coil 16 is reactively coupled to this coil 8 and is connected between the grid and the filament to serve as a means for exciting the thermionic generator. 25 Finally a source of electromotive force is applied across the anode and filament of the thermionic element.

According to the present invention, there 30 is arranged in series with the coil 16 between the grid and the filament, an impedance formed by an inductance 10 and a capacity 11 connected in parallel and substantially tuned to the wave-length of the thermionic generator.

35 This impedance can easily be made very large and of the order of magnitude of the resistance of the thermionic element between grid and filament.

40 The microphone 12 is placed, for instance, in series with the inductance. Under this condition, the impedance is proportional to the microphone resistance and the variations of microphone resistance give corresponding variations in the impedance. It 45 may be said that the arrangement functions as if one had substituted for a microphone of low resistance a very high resistance microphone (of the order of magnitude of the resistance of the thermionic element between grid and filament) and is more suitable for controlling the grid-filament current of the oscillating thermionic element.

In the arrangement described above, it is obvious that the microphone 12 can be placed in series with the capacity 11 to obtain the 55 same results.

Figure 2 shows a second method of carrying out the invention. It will be seen that the usual arrangement of thermionic generator is to be found which is lettered with 60 similar reference letters to the arrangement shown in Figure 1.

The arrangement of microphone is different. A second thermionic element 13 has its anode-filament circuit connected in series in 65 the grid-filament circuit of the transmitting generating thermionic element 1. This second thermionic element consequently receives across its anode and filament the voltage existing across the grid and filament 70 of the thermionic element 1. The microphone 12 is placed in series with a battery 14 and the primary winding of a transformer 15, the secondary of which is connected between the grid and filament of the 75 thermionic generator 13.

It will be seen that in this arrangement the variations of microphone current will influence the maintaining of oscillations in the sending thermionic valve generator 1.

Having described my invention, what I claim is:

1. A radio signaling system comprising means for radiating oscillations, a three-electrode thermionic oscillation generator associated with said radiating means, and means for influencing the output energy of said oscillation generator, said means including a three-electrode thermionic tube in series with the grid-filament circuit of said oscillator.

2. In a signaling system, a transmission circuit, a three electrode thermionic oscillation generator coupled to said transmission circuit, and means for influencing the output energy of said oscillation generator, said means including a modulating three electrode thermionic tube in series with the grid-filament circuit of said oscillation generator.

3. In a signaling system, an oscillation generator comprising a thermionic tube provided with an input circuit and an output circuit, modulating means for controlling

said oscillation generator including a thermionic tube having a filament, a control electrode, and a plate, the input circuit of said generator serially including the plate and 5 filament of said second thermionic tube, and signal-controlled means for governing said control electrode.

4. In a signaling system, an oscillation generator comprising a thermionic device 10 provided with input and output circuits, a modulating thermionic tube having a filament, a plate and a grid, said filament and said plate being serially included in said input circuit, a circuit including said grid 15 and said filament, and means including a signal-controlled device for introducing energy into said last mentioned circuit.

5. In a signaling system, an oscillation generator comprising a thermionic device

provided with reactively coupled input and 20 output circuits, a second thermionic device including an input electrode and an output electrode, said output electrode being serially included in said input circuit and signal-controlled means associated with said input 25 electrode for governing said input circuit.

6. In a signaling system, a transmission circuit, a three-electrode discharge device having an anode-cathode circuit coupled to said transmission circuit, a grid-cathode circuit for said discharge device, a three-electrode modulating device having its output circuit serially included in said grid-cathode circuit, an input circuit for said modulating device, and signal-controlled means for 30 35 variably controlling said input circuit.

MARIUS LATOUR.
